US0D1094828S

(12) **United States Design Patent** (10) **Patent No.:** **US D1,094,828 S**
(45) **Date of Patent:** **** Sep. 23, 2025**

(54) **LAMP**

(71) Applicant: **Dan Zhao**, Zhongshan (CN)

(72) Inventor: **Dan Zhao**, Zhongshan (CN)

(**) Term: **15 Years**

(21) Appl. No.: **29/941,845**

(22) Filed: **May 13, 2024**

(51) **LOC (15) Cl.** **22-06**

(52) **U.S. Cl.**

USPC **D22/123**

(58) **Field of Classification Search**

(57) **CLAIM**

The ornamental design for a lamp, as shown and described.

DESCRIPTION

FIG. 1 is a perspective view of lamp, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings depict portions of the lamp, that form no part of the claimed design.

1 Claim, 7 Drawing Sheets
